UNITED STATES PATENT OFFICE.

HARRY C. HOWER, OF CHICAGO, ILLINOIS.

DESIGN FOR AN AUTOMOBILE TIRE.

Application filed July 16, 1926. Serial No. 18,381. Term of patent 14 years.

To all whom it may concern:

Be it known that I, HARRY C. HOWER, a citizen of the United States, residing at Chicago, in the county of Cook and State of Illinois, have invented a new, original, and ornamental Design for Automobile Tires, of which the following is a specification, reference being had to the accompanying drawings, forming a part thereof.

Fig. 1 is a perspective view of the tire;

Fig. 2 is a plan view of a portion of the tire; and

Fig. 3 is a transverse section on the line 3—3 of Fig. 2.

I claim:

The ornamental design for an automobile tire as shown.

In witness whereof, I hereunto subscribe my name this 14th day of July, 1926.

HARRY C. HOWER.
